J. H. OBERMAN, JR.

PUMP OPERATING MECHANISM

Original Filed Dec. 11, 1922

Patented June 24, 1924.

1,498,807

UNITED STATES PATENT OFFICE.

JOSEPH H. OBERMAN, JR., OF GRANVILLE, IOWA.

PUMP-OPERATING MECHANISM.

Original application filed December 11, 1922, Serial No. 606,108. Divided and this application filed August 29, 1923. Serial No. 659,961.

To all whom it may concern:

Be it known that I, JOSEPH H. OBERMAN, Jr., a citizen of the United States, residing at Granville, in the county of Sioux and 5 State of Iowa, have invented certain new and useful Improvements in Pump-Operating Mechanism, of which the following is a specification.

This application is a division of an application filed by me December 11, 1922, Serial No. 606,108.

The present invention seeks to provide novel means whereby a pump plunger may be easily reciprocated and will be held to 15 a rectilinear path, and also to provide a construction which will facilitate assembling and disassembling of the parts and firmly support the operating lever when the parts are assembled. These stated objects and 20 other incidental objects which will appear in the course of the following description are attained in such an apparatus as is illustrated in the accompanying drawing, and the invention resides in certain novel features which will be particularly pointed out 25 in the appended claims.

In the drawing:

Figure 1 is a side elevation of so much of a pump as is needed to show my present 30 invention;

Fig. 2 is a rear elevation, and

Fig. 3 is a vertical section.

The pump is supported by a well curb or platform (not shown) and includes a 35 standard or sustaining tube 9.

On the upper end of the standard or sustaining tube 9, I secure a cap 29 which is provided on its upper side with flanges or lugs 30 to which the head or bracket 31 is 40 secured. The said head or bracket consists of side members provided at their lower ends on their inner faces with recesses 32 corresponding in dimensions and form to the lugs 30 so that, when the bracket or head is 45 in the position shown in Fig. 1 and the bolts 33 are in place, the bracket will be firmly supported in proper position to guide the plunger rod. Upon its outer side, one of the side members is provided with a ledge 50 or shoulder 34 against which the heads 35 of the bolts 33 may bear so that the bolts will be prevented from turning while the nuts 36 are driven home, the necessity of employing an extra wrench or other tool to 55 prevent turning of the bolt being thus over-

come. The side plates or members of this bracket or head are connected at their upper ends by a cap plate or bar 37 which is secured to and between the side plates by 60 bolts 38 inserted therethrough, and it will be readily noted upon reference to Fig. 1 that the upper extremities of the said side plates are disposed out of vertical alignment with the sustaining rod 9 whereby 65 the plunger rod may be slidably fitted through the said guide plate 37. At their lower ends, the side plates are further connected by a guide bar or plate 39 which is secured in place by bolts 40, and both 70 guide plates 37 and 39 are provided centrally with angular openings 41 through which the flat bar 42, which constitutes the upper extremity of the plunger, is slidably fitted. One side plate is further provided with a 75 ledge or shoulder 43 on its outer side against which the heads of the bolts 40 may bear so that these bolts will be prevented from turning while the securing nuts are driven home, and a similar ledge or shoulder 44 is 80 provided adjacent the upper end of the side plate to prevent turning of the bolts 38. A fulcrum post 45 is mounted upon the cap 29 between the flanges or lugs 30 and projects upwardly and outwardly therefrom, as 85 clearly shown in Fig. 1, the lower end of the post being pivotally held by the outer bolt 33. A hand lever 46 is fulcrumed upon the upper end of this post 45 and has its inner end pivotally attached to the bar 42 so that 90 by oscillating the hand lever, the plunger will be reciprocated and the pump operated.

The lower end of the bar 42 is secured within a yoke 47 which is firmly secured upon the upper end of the plunger rod 48. 95 The plunger rod extends down into the working cylinder and carries a plunger within the cylinder, as will be understood.

If repairs to the plunger or the cylinder should be necessary, the flat bar 42 which 100 constitutes the upper extremity of the plunger rod is disconnected and removed from the guide bars or plates 39 and 37. The inner bolt 33 is then removed and the bracket or head 31 may then be swung rearwardly about the outer bolt 33 as a pivot. Ready access may then be had to the plunger and cylinder to repair or renew the parts.

Having thus described the invention, what is claimed as new is:

1. In a pump, the combination of a sus-

2
taining member, a head consisting of side plates disposed at the upper end of the sustaining member, guides disposed between the side plates at one side of the vertical plane 5 of the sustaining member, securing bolts inserted through the side plates and the guides and through the side plates and the upper end of the sustaining member respectively, a plunger rod disposed at the side 10 of the sustaining member and playing in the guides, and means mounted on the sustaining member to operate the plunger rod.

2. In a pump, the combination of a sustaining member, a plunger rod, flanges on 15 the upper end of the sustaining member, a head comprising side plates disposed against said flanges, bolts fitted through said flanges and the said side plates, one of said bolts being removable to permit pivotal adjust-

ment of the side plates upon the remaining bolt, guides carried by said side plates and receiving the upper extremity of the plunger rod, and an operating member mounted upon the sustaining member and connected with the said plunger rod. 20

3. In a pump, the combination of a sustaining member, a head, means whereby the head may be secured rigidly upon the sustaining member or permitted a rocking movement thereon, a plunger rod, means on the head to guide the plunger rod, a fulcrum 25 post pivotally mounted on the head, and an operating lever fulcrumed on said post and extending through the head and connected with the plunger rod. 30

In testimony whereof I affix my signature.

JOSEPH H. OBERMAN, JR. [L. S.]
